UNITED STATES PATENT OFFICE.

FREDERICK W. LETSCH, OF BALTIMORE, MARYLAND.

MATRIX HOLDER AND ELEVATOR FOR TYPOGRAPHIC MACHINES.

1,410,330.

Specification of Letters Patent. Patented Mar. 21, 1922.

Original application filed March 15, 1918, Serial No. 222,760. Divided and this application filed July 12, 1920. Serial No. 395,579.

To all whom it may concern:

Be it known that I, FREDERICK W. LETSCH, a citizen of the United States, and residing at Baltimore city, Maryland, have invented 5 certain new and useful Improvements in Matrix Holders and Elevators for Typographic Machines, of which the following is a specification.

This invention relates to a matrix holder 10 and elevator for typographic machines, particularly machines of the kind disclosed in my copending application, Serial No. 222,760, filed March 15, 1918, of which the present application is a division.

15 The invention relates particularly to the mechanism for receiving the matrices from the assembler mechanism, presenting them to the mold and after the casting operation elevating the same to the position to be 20 transferred to the distributing mechanism. It is the principal aim of the invention to simplify the mechanism employed for accomplishing these results and to provide a construction which is positive and rapid in 25 operation and which, if desired, may be easily arranged to produce repeated castings from the same matrix.

30 The invention in one of its embodiments is set forth in detail in the following specification and illustrated in the accompanying drawings in which:

35 Figure 1 is a sectional view of a portion of a typographical machine, said view being taken on a vertical plane from front to rear through the parts of the mechanism constituting the present invention and other parts which co-operate therewith:

40 Figure 2 is a horizontal sectional view through a portion of a machine embodying the present invention and showing the relation of the present improvement to other parts of the mechanism;

45 Figure 3 is a front elevation of a part of the mechanism illustrated in Figure 1;

50 Figure 4 is an enlarged sectional view of parts of the mechanism appearing in Figure 1;

55 Figure 5 is a sectional view on the line 5—5 of Figure 4, looking in the direction of the arrows;

Figure 6 is a sectional view on the broken line 6—6 of Figure 4, looking in the direction of the arrows;

Figure 7 is an enlarged sectional view

similar to Figure 4 but showing certain parts 55 in a different position;

Figure 8 is a detailed view of a locking device employed when making duplicate linotype castings.

Referring to the drawings in detail 10 represents generally the assembling mechanism in which the matrices and space bands are assembled to form a line in the well known manner and as set forth in my prior application above mentioned and from which 60 mechanism the matrices are transferred to the part of the machine to which the present invention relates. 11 represents generally 65 the mold to which the assembled matrices are presented in casting slugs or linotypes, such 70 mold being of any desired construction.

The mechanism to which the present invention particularly relates, includes a presentation slide 16 which carries fixed rails 12, 13 and 15 and a movable rail 14. These 75 rails are adapted to receive the assembled matrices and space bands from the assembling mechanism and support the same during the casting operation and while they are elevated as hereinafter pointed out. The 80 presentation slide is arranged to move forward and rearward upon guides or ways 17 and the same is also movable vertically in guide-ways 18 formed in suitable standards or rigid portions of the framework of the 85 machine. The presentation slide when in its forward position and withdrawn from the mold is adapted to slide vertically in said guideways 18 to carry the matrices to the second elevator and to carry the space 90 bands associated with the matrices to the level of the space band magazine as fully set forth in my said prior application, the presentation slide 16 thus constituting the first 95 elevator. The presentation slide 16 is moved rearward and forward or toward and from

the casting mechanism by two pairs of elbow levers 19 pivoted to a rigid part of the machine and which have downwardly projecting arms provided with rollers 20 running 100 in guide grooves 21 of said slide 16. The elbow levers also have forwardly extending arms which are connected to cross bars 22 which cross bars are connected by suitable links 23. The elbow levers 19 are rocked 105 to carry the presentation slide rearward and forward by a rod 24 which is operated by a suitable cam mechanism secured to the main

cam shaft of the machine. The detailed mechanism employed for operating said rod constitutes no part of the present invention and description and illustration of the same 5 is unnecessary. The rod 24 includes a spring link 25 of ordinary construction, the details of which it is not necessary to illustrate.

It will be understood that as the rod 24 10 is drawn downwardly the elbow levers will be rocked on their pivots and the presentation slide 16 will be moved rearwardly to bring the matrices against the mold. In order that the matrices may be brought into 15 exact register with the mold there is provided dowel pins 11^a rigidly secured to a part of the casting mechanism which dowel pins are adapted to enter openings 16^a in the presentation slide. When the rod 24 is 20 moved upwardly the presentation slide will be drawn forwardly or away from the mold. The operation of casting the slugs or linotypes takes place while the presentation slide carrying the matrices is in its rear- 25 ward position or against the mold.

When it is desired to cast a plurality of slugs or linotypes from a single line of matrices the rod 24 is prevented from rising to its full extent and the elbow levers 19 30 are therefore prevented from withdrawing the presentation slide sufficiently to engage it with the elevating device hereinafter described. This result is accomplished by interposing a pivoted block 26 in the path of 35 a collar 27 which is secured on the rod 24. This prevents upward movement of the rod 24, the movement of the operating mechanism which causes reciprocation of the rod 24 being taken up, under such condition, 40 by the spring link 25. When the block 26 is rotated about its pivot point 26^a so as to be out of the path of movement of the collar 27 a single slug or linotype will be cast from each line of assembled matrices.

45 When the rod 24 is raised to its full extent and the presentation slide is moved to the positions shown in Figures 1 and 4, a cross bar 30 at the bottom of the slide enters a recess or opening 31 in the upper end 50 of an elevator slide 32. The elevator slide 32 is operated in proper timed relation to the rest of the mechanism by a suitable cam secured to the main cam shaft of the machine. It will be understood that when the 55 forward movement of the presentation slide is interrupted by the pivoted block 26, as previously stated, the cross bar 30 will not be moved forwardly a sufficient distance to engage the opening 31 of the elevator slide 60 32 and the upward movement of said elevator slide will not raise the presentation slide. When the parts are in the position shown in Figures 1 and 4 the presentation 65 slide will be raised in the guides 18 by the upward movement of the elevator slide 32.

During such upward movement of the presentation slide the movable matrix-supporting rail 14 will be withdrawn through the medium of the lever 33 which is pivoted to the presentation slide 16 which carries 70 at its free end a roller 34 positioned to contact with the incline 35 arranged adjacent the upper part of the guide-ways 18. The rail 14 is adapted to support the matrices when it is desired to cast from the lower 75 row of characters usually provided on the matrices and it therefore follows that when this rail is withdrawn in the manner just described the matrices will all be brought to a common level suitable for transfer to 80 the second elevator which is of well known type and which it is unnecessary to illustrate or describe in the present application, such transfer being effected by suitable transfer mechanism generally designated by 85 the numeral 36.

To briefly review the operation of the device it will be understood that the matrices are assembled in suitable lines in the assembling mechanism and that such assembled lines are then transferred to the presentation slide of the present mechanism being supported on the rails with which such slide is provided. The rod 24 is caused to move up and down by suitable cam mechanism operated from the main shaft of the machine. As this rod moves downwardly the elbow levers are rocked on their pivots which cause the presentation slide to move rearwardly against the casting mechanism. 100 After the casting operation the rod 24 moves upwardly which serves to withdraw the presentation slide and the line of matrices mounted therein from the casting mechanism. If the upward movement of the rod 24 is interrupted by means of the locking mechanism 26 the presentation slide will be moved only a short distance from the casting mechanism, and upon the next downward movement of the rod the presentation slide 110 with the same matrices mounted thereon will be again presented to the mold and a second slug or linotype of the same character will be cast. If the upward movement of the rod 24 is not interrupted the presentation slide will be drawn forwardly to the full extent of its movement and the cross bar 30 on said slide will enter the recess 31 of the elevator slide 32 and as said elevator slide is moved upwardly the presentation 120 slide will be raised in the guide-ways 18 thus lifting the line of matrices in position to be transferred to the second elevator. During such upward movement of the presentation slide the rollers carried by the elbow 125 levers will move freely in the grooves formed in the presentation slide and such rollers and elbow levers will therefore not interfere with the upward or downward movement of the presentation slide. As the ele- 130

vator slide 32 moves downwardly the presentation slide is lowered to its original position ready to receive a new line of assembled matrices from the assembler mechanism.

5 It is obvious that various modifications and rearrangements of the foregoing mechanism may be made without departing from the spirit of the invention and which is not limited to the particular details of construction and operation herein described.

10 Having thus described my invention what I claim as new and desire to secure by Letters Patent is:

1. In a typographic machine comprising 15 a matrix assembling mechanism and a casting mechanism, a presentation slide movable horizontally in a straight line toward and from the mold to carry the matrices to and from casting position and movable vertically 20 in a straight line to deliver the matrices to the second elevator, and means for alternately moving the slide horizontally and vertically.

2. In a typographic machine having a 25 matrix assembling mechanism and casting mechanism, a presentation slide having supports to receive a line of matrices, a stationary guideway for said slide, means for moving said slide to and from the mold, and 30 means for moving said slide vertically on said guideway when it is away from the mold to raise the matrices into register with the second elevator.

3. In a typographic machine having a 35 matrix assembling mechanism and casting mechanism, a presentation slide having supports to receive a line of matrices, means for moving said slide to and from the mold, and means for moving said slide vertically when 40 it is away from the mold to raise the matrices into register with the second elevator, said latter means comprising a vertically movable slide having an opening adapted for engagement with a part of the presentation slide when the latter is withdrawn from the casting mechanism.

4. In a typographic machine, the combination with a mold, of a presentation slide having means for supporting a line of matrices, horizontal ways on which said presentation slide is movable toward and from the mold, vertical ways on which said presentation slide is vertically movable, and means for reciprocating said presentation 55 slide horizontally and vertically alternately.

5. In a typographical machine having matrix assembling mechanism and casting mechanism, the combination with a mold, of a presentation slide having means for 60 supporting a line of matrices, horizontal ways on which said presentation slide is movable toward and from the mold, vertical ways on which said presentation slide is vertically movable, means for reciprocating 65 said presentation slide horizontally and ver-

tically alternately and dowel pins and sockets on the mold and presentation slide for bringing the matrices into exact register with the mold when the slide is moved toward the mold.

6. In a typographic machine having matrix assembling mechanism and casting mechanism, the combination with a mold, of a presentation slide having means for supporting a line of matrices, vertical grooves 75 in said slide, means operating in said groove for imparting horizontal movement to the slide without restraining vertical movement thereof, and means for moving said slide vertically when it is withdrawn from the 80 mold to carry the matrices to a higher level.

7. In a typographic machine, in combination, a matrix assembling and a casting mechanism, a presentation slide, means for moving the slide horizontally toward and 85 from the mold, and means for moving the slide vertically when the same is withdrawn from the mold, said last named means being disengaged from the slide as the same is moved toward the mold by said first named 90 means.

8. In a typographic machine having matrix assembling mechanism and casting mechanism, the combination with a mold, of a presentation slide movable horizontally 95 toward and from the mold, an elevating device with which said slide engages when moved away from the mold, and means for preventing engagement of the presentation slide with the elevating device to thereby 100 prevent distribution of the matrices and obtain duplicate castings therefrom.

9. In a typographic machine having matrix assembling and casting mechanism, the combination with a mold, of a presentation 105 slide adapted to support a plurality of matrices, means for moving said slide toward and away from said mold, means for elevating said slide when withdrawn from said mold to the normal degree and means for 110 preventing withdrawal of said slide to the normal degree to thereby prevent distribution of the matrices and obtain duplicate castings therefrom.

10. In a typographic machine having a 115 matrix assembling and casting mechanism, the combination of a mold, a presentation slide having means for supporting matrices, vertical grooves in said slide, a plurality of bell-crank levers pivoted to the frame of the 120 machine, one end of each of said levers carrying a roller arranged to travel in one of said grooves, means connected to the other ends of said levers for operating the same to move said slide toward and from the 125 mold, and means for moving said slide vertically when it is withdrawn from the mold.

In testimony whereof I affix my signature.

FREDERICK W. LETSCH.
